US0D1082454S

(12) **United States Design Patent** (10) **Patent No.:** **US D1,082,454 S**
(45) **Date of Patent:** **** Jul. 8, 2025**

(54) **KNIFE**

(71) Applicant: **Robert Welch Designs Ltd.,**
Gloucestershire (GB)

(72) Inventor: **Iain Paul deBretton Gordon**, Shipston
on Stour (GB)

(73) Assignee: **Robert Welch Designs Ltd.,**
Gloucestershire (GB)

(**) Term: **15 Years**

(21) Appl. No.: **29/919,792**

(22) Filed: **Dec. 6, 2023**

(30) **Foreign Application Priority Data**

Jun. 13, 2023 (GB) 6289728
